UNITED STATES PATENT OFFICE

92,230

DESIGN FOR A LIP STICK CONTAINER

Edna May Cox, New York, N. Y.

Application August 17, 1933, Serial No. 49,049

Term of patent 3½ years

To all whom it may concern:

Be it known that I, EDNA MAY Cox, a citizen of the United States, residing at New York city, in the county of New York and State of New York, have invented a new, original, and ornamental Design for Lip Stick Containers, of which the following is a specification, reference being had to the accompanying drawing, forming part thereof.

In the drawing,

Figure 1 is a perspective view and

Figure 2 is a front elevation of a lip stick container showing my new design.

I contemplate employing any suitable colors but prefer colors in simulation of a finger tip and nail for the outer end of the container.

I claim:

The ornamental design for a lip stick container, as shown and described.

EDNA MAY COX.
